WARP KNITTING MACHINE

Fritz Lambach, Tenafly, N. J., assignor to Robert Reiner, Inc., Weehawken, N. J.

Application November 7, 1951, Serial No. 255,206

25 Claims. (Cl. 66—86)

1

This invention relates to warp knitting machines, and more particularly to an automatic device for controlling the pattern mechanism of a warp knitting machine.

An object of the present invention is to provide a warp knitting machine by means of which complicated patterns may be knitted without the use of extremely long pattern chains, which are expensive and difficult to assemble.

Another object of the present invention is to provide a warp knitting machine which may be advantageously used for the knitting of fabrics having patterns with repeating motives.

A further object of the invention is to provide a warp knitting machine having an automatic device for controlling the pattern mechanism of such a construction that the machine may be operated at comparatively high speed.

Another object of the invention is to provide a warp knitting machine with an automatic device for controlling the pattern mechanism, which automatic device may be readily rendered inoperative, if it is desired to operate the machine with standard pattern mechanism equipment.

Still another object of the invention is to provide a warp knitting machine with means for accelerating and decelerating the speed of the pattern chain drum at predetermined intervals during the operation of the machine, if so desired.

A further object of the present invention is to improve on the construction of warp knitting machines as now customarily made.

Other objects and structural details of the invention will be apparent from the following description when read in conjunction with the accompanying drawings forming part of this specification, wherein:

Fig. 1 is a front elevational view of a warp knitting machine according to the invention.

Fig. 2 is a fragmentary front elevational view, in an enlarged scale, illustrating a portion of the guide bars and means for displacing same.

Fig. 3 is a sectional view, taken on line 3—3 of Fig. 2.

Fig. 4 is a fragmentary elevational view of the warp knitting machine as seen in the direction of the arrow 4 shown in Fig. 1.

Fig. 5 is an elevational view of a portion of the machine as seen in the direction of the arrow 5 shown in Fig. 4.

Fig. 6 is a fragmentary sectional view taken on line 6—6 of Fig. 5.

Fig. 7 is an elevational view of the same portion of the machine as seen in the direction of the arrow 7 shown in Fig. 4.

2

Fig. 8 is a sectional view taken on line 8—8 of Fig. 4.

Fig. 9 is an enlarged elevational view of a portion of the machine shown in Fig. 4.

Fig. 10 is an elevational view of the portion shown in Fig. 9 as seen in the direction of the arrow 10 shown in said Fig. 9.

Fig. 11 is a top plan view of the device shown in Fig. 10.

Fig. 12 is a fragmentary perspective view of a linkage shown in Fig. 7.

Fig. 13 is a fragmentary perspective view of another linkage shown in Figs. 7 and 9, and

Figs. 14—16 are top plan views illustrating a selector mechanism of the machine in various positions.

The drawings illustrate only those parts of a warp knitting machine which are necessary for the understanding of the invention.

Hereinafter the invention will be described in connection with a so called "Raschel Machine," however, it is understood that the invention may be applied also to different types of warp knitting machines.

Referring now to Fig. 1, 20 generally indicates the frame of a warp knitting machine comprising end frames 22, 24, connected with each other by tubes 26 (only one being shown). A main cam shaft 28 journaled in suitable bearings of the frame 20 may be rotated by an electric motor 30 through the medium of a belt drive generally indicated by 32.

As best shown in Figs. 1 and 4 the main cam shaft 28 rotates through a train of gears 34, 36, 38, 40, and 42, a second cam shaft 44 journaled in suitable bearings of the frame 20 of the machine.

As best shown in Figs. 1—3 a guide bar shaft 46 rotatably and axially immovably arranged in the frame 20 of the machine carries a series of hangers 48 rigidly secured thereto by screws or the like. In a manner known per se a series of eight guide bars 50—1, 50—2, 50—3, 50—4, 50—5, 50—6, 50—7, and 50—8, carrying a plurality of warp guides 52 are suspended from the hangers 48 in such a way that on one hand they can be shifted in the direction of the longitudinal axis of the machine and that on the other hand they participate in any rocking movement of the guide bar shaft 46 about the longitudinal axis of the latter. The guide bar shaft 46 may be periodically rocked in a manner known per se by means of an actuating mechanism generally indicated by 54 (see Fig. 1) driven by a cam 56 keyed to the main cam shaft 28.

In a manner known per se cams 57 (Fig. 1) secured to the main cam shaft 28 rock periodically, thereby actuating mechanisms generally indicated by 59, a needle bar shaft 61 journalled in suitable bearings of the frame and connected with a needle bar 63 carrying the needles 65.

As best shown in Figs. 1 and 2, each of the guide bars 50-1, 50-2 . . . 50-8 carries an adjustable contact element 58 at its left hand end. Between each guide bar 50-1, 50-2 . . . 50-8 and a holding element 60 secured to the guide bar shaft 46, a tension spring 62 is stretched, which tends to urge the contact element 58 of the associated guide bar into engagement with an abutting plate 64 carried by a slider 66-1 or 66-2 . . . or 66-8 associated with the respective guide bar 50-1 or 50-2 . . . or 50-8. Each of the eight sliders 66-1, 66-2 . . . 66-8 is shiftably arranged in a housing 68 mounted in a suitable manner on the frame of the machine.

The sliders 66-1, 66-2, 66-7, and 66-8 associated with the guide bars 50-1, 50-2, 50-7 and 50-8 carry rollers 70 for engagement with link pattern chains 72-1, 72-2, 72-7 and 72-8 trained around an upper pattern chain drum 74 rotatably arranged in the machine (see Figs. 1, 2, 4, and 5). The sliders 66-3, 66-4, 66-5 and 66-6 have straight ends arranged for engagement with the curved portion of the upper end 76-3, 76-4, 76-5 and 76-6 of pattern arms or controlling arms 78-3, 78-4, 78-5 and 78-6 respectively (see Figs. 4 and 8). These pattern arms 78-3, 78-4, 78-5 and 78-6 are rotatably mounted on a shaft 80 carried by the frame of the machine.

As best shown in Figs. 2 and 5 each of the sliders 66 carries a projection 82 capable of engagement with an arm 84 secured to a shaft 86 rotatably mounted in a bracket 87 attached to the frame of the machine. As best shown in Figs. 1, 2, 4, and 5 a hand lever 88 is secured to the projecting end of the shaft 86. Normally this hand lever 88 is in the position shown in full lines in said figures. If it is desired to disengage all of the sliders 66-1, 66-2 . . . 66-8 from the pattern chains 72-1, 72-2 . . . 72-8 and the upper ends of the pattern arms 78-3, 78-4, 78-5, and 78-6 respectively during a standstill of the machine, the hand lever 88 is swung in counterclockwise direction, so that the arms 84 reach the position 84' as shown in Fig. 2, whereby the projections 82—and of course, the sliders 66 connected therewith—are displaced into the position 82'. The hand lever 88 may be held in the position for disengagement of the sliders 66-1, 66-2 . . . 66-8 from the pattern chains and pattern arms by means of a swingable toothed locking element 90 (Figs. 4 and 5) arranged for engagement with a pin 92 projecting from the hand lever 88. Upon release of the hand lever 88 by said locking element 90 the return springs 62 return the guide bars 50-1, 50-2 . . . 50-8 together with the sliders 66 into such a position that the sliders 66-1, 66-2 . . . 66-8 again are in engagement with the pattern chains 72-1, 72-2 . . . 72-8 and pattern arms 78-3, 78-4, 78-5 and 78-6 respectively.

As best shown in Fig. 4, the upper pattern chain drum 74 rigidly connected with a shaft 94 journalled in suitable bearings of the bracket 87 attached to the frame of the machine is provided with a series of grooves. The pattern chains 72-1, 72-2, 72-7 and 72-8 are engaged with the grooves 96-1, 96-2, 96-7 and 96-8 respectively. The grooves 96-3, 96-4, 96-5 and

96-6 arranged between the grooves 96-2 and 96-7 are free from pattern chains in the embodiment shown in the drawings.

As best shown in Fig. 1, each of the pattern chains 72 constituted by link chains trained around the upper pattern chain drum 74 and two idling rollers 98 and 100 are adjustably mounted on an upright 102 connected with the bracket 87 by bars 104.

10 The upper pattern chain drum 74 may be rotated by the following mechanism:

As best shown in Figs. 4 and 5 a sprocket wheel 106 is rigidly connected with the main cam shaft 28 rotated by the motor 30 through the belt drive

15 32. A chain 108 tensioned by an adjustable tensioning device 110 is trained around said sprocket wheel 106 and another sprocket wheel 112 secured to a shaft 114 rotatably and axially immovably arranged in a housing 116 attached to

20 the bracket 87 carried by the frame of the machine. A member generally indicated by 118 (see Figs. 4-6) comprising a cam portion 120 and a worm portion 122 is slidably engaged with a spline 124 carried by the shaft 114; thus the member

25 118 on one hand may be displaced in the direction of the longitudinal axis of the shaft 114 relative to the latter and on the other hand participates in a rotation of said shaft 114. The cam portion 120 has two tracks 126 and 128.

30 The track 126 being a circular track is arranged for engagement with a roller 130 carried by a setting pin 132 shiftably mounted in a sleeve 134 carried by and projecting from the housing 116. The setting pin 132 may be held in a predetermined position for engagement with or disengagement from the track 126 by means of a set screw 136.

35 The track 128 of the cam portion 120 constituting a track of a drum cam is arranged for engagement with a roller 138 carried by another setting pin 140 slidably arranged in a sleeve 142 carried by and projecting from the housing 116.

40 The setting pin 140 may be held in a predetermined position for engagement with or disengagement from the track 128 by means of a set screw 144.

45 As will be readily understood, if the roller 130 of the setting pin 132 is engaged with the circular track 126 and the roller 138 of the setting pin 140 is out of engagement with the drum cam track 128, the member 118 including the cam 120 and the worm 122 remains in the same position relative to the shaft 114 during a rotation thereof. If, however, the roller 130 of the setting pin 50 132 is disengaged from the circular track 126 and the roller 138 of the setting pin 140 is engaged with the drum cam track 128, the member 118 including the cam portion 120 and worm 122 is moved back and forth in the direction of the longitudinal axis of the shaft 114 during a revolution of the shaft 114. It is understood that the contour of the drum cam is made in such a way that it suits the shifting movements as desired for a purpose to be described later on.

55 60 65 The worm 122 is in mesh with a worm gear 146 (Figs. 4 and 5) keyed to the shaft 94 carrying the upper pattern chain drum 74. Thus, when the main shaft 28 is rotated, the shaft 94 and the upper pattern chain drum 74 are continuously rotated through the chain drive 108 and the worm drive 122, 146. If, upon engagement of the setting pin 132 with the circular track 126 of the cam 120 the worm 122 remains in its position relative to the shaft 114, the shaft 94 and the upper pattern chain drum 74 will be rotated at

constant speed; if, however, upon engagement of the setting pin 140 with the drum cam track 123 the worm 122 is displaced back and forth relative to the shaft 114, the speed of the shaft 94 and upper pattern chain drum 74 is accelerated and decelerated in dependence on the shape of the contour of the drum cam track determining the shifting of the worm 122 relative to the worm gear 146 during the rotation of the worm 122.

As best shown in Figs. 4 and 7 a sprocket wheel 148 is keyed to the shaft 94 carrying the upper pattern chain drum 74. A chain 150 is trained around said sprocket wheel 148 and another sprocket wheel 152 of the same size, keyed to a shaft 154 journaled in suitable bearings of the bracket 87 attached to the frame of the machine. A lower pattern chain drum generally indicated by 156 is rigidly connected with said shaft 154, so that this lower pattern chain drum 156 is continuously rotated at the same speed as the upper pattern chain drum 74.

As best shown in Fig. 4, the lower pattern chain drum 156 has a series of grooves 158-3-a, 158-3-b, 158-3-c, 158-4-a, 158-4-b, 158-4-c, 158-5-a, 158-5-b, 158-5-c, 158-6-a, 158-6-b, 158-6-c and 160. Each of said grooves receives a link chain trained around said lower pattern chain drum and adjustable idling rollers 162 and 164 mounted on the upright 102 as shown in Fig. 1. Fig. 4 shows only the pattern chains 166-5-a, 166-5-b, 166-5-c and 168, engaged with the grooves 158-5-a, 158-5-b, 158-5-c and 160 respectively.

As best shown in Figs. 4, 9 and 13, the link pattern chain 168 engaged with the groove 160 of the lower pattern chain drum 156 cooperates with a roller 170 carried by a controlling arm 172. As best shown in Fig. 7 the controlling arm 172 is swingably mounted on a shaft 174 carried by the bracket 87 attached to the frame of the machine. A spring 175 stretched between a rod 177 of the bracket structure and said controlling arm 172 tends to urge the roller carried by the latter into engagement with the associated link chain trained around the lower pattern chain drum 156. According to Figs. 4, 9 and 13, a bracket 176 secured to the controlling arm 172 is in abutting engagement with an adjustable stop 178 carried by the arm 180 of a double-armed lever 182 swingably mounted on a stud 184 carried by the frame of the machine. The other arm 186 of said double-armed lever 182 is pivotally connected at 188 with the upper end of a link 190, the lower end of which is pivoted at 192 with the arm 194 of a double-armed lever 196 swingably mounted on a shaft 198 carried by the bracket 87 attached to the frame of the machine. As best shown in Figs. 9-11, the other arm 200 of the double-armed lever carries a spring-loaded actuating pawl 202 rockably mounted thereon at 204. The actuating pawl 202 is arranged for corporation with teeth of a ratchet wheel 206 rigidly connected with a controlling drum generally indicated by 208, rotatably mounted on the shaft 198. A locking pawl 210 swingably mounted on a shaft 212 carried by the bracket 87 attached to the machine is capable of engagement with teeth of the ratchet drum 206 connected therewith in a position wheel 206 for holding same and the controlling drum 208 wherein it has been advanced by an actuation of the actuating pawl 202.

As will be readily understood, when, during the rotation of the lower pattern chain drum 156, a high portion of the link pattern chain 168 lifts

the controlling arm 172, the controlling drum 208 is advanced a step by means of the actuating pawl 202 in the direction of the arrow A (see Fig. 4).

5 A ladder chain 214 carrying a number of buttons is trained around the controlling drum 208 and an idling roller 216 (see Fig. 4) carried by a downwardly projecting rod 218.

10 According to the embodiment shown in the drawings, the chain 214 has a row of buttons 220s and another row of buttons 220y (see Fig. 11).

15 The row of buttons 220y is carried for cooperation with a jack 222 (see Figs. 9, 10 and 11) swingably mounted on a shaft 224 carried by the bracket 87. A pin 226 projecting from the upper end of the jack 222 is in slidable engagement with a slot 228 of a yoke 230 rockably mounted on a shaft 232 carried by the bracket. A spring 234 (see Fig. 9) stretched between a stationary point 236 and a projection 238 of the jack 222 tends to urge same in clockwise direction, against the shaft 232 acting as a stop, so that a downwardly extending arm 240 of the yoke 230 is held in the position shown in full lines in Fig. 9. In said position the end 240 of the yoke 230 holds a spring-loaded actuating pawl 242 swingably mounted at 244 on the arm 246 of a double-armed lever 248 out of engagement with teeth of a ratchet wheel 250 rigidly connected with a selector drum generally indicated by 252. Said selector drum 252 is rotatably mounted on the shaft 198 of the bracket structure.

20 As will be readily understood, a movement of the actuating pawl 242 by the double-armed lever 248 in a manner to be described hereinafter, has no influence on the ratchet wheel 250 and the selector drum 252 connected therewith, as long as said actuating pawl 242 is held out of engagement with teeth of the ratchet wheel 250 by the end 240 of the yoke 230 as shown in full lines in Fig. 9. If, however, a button 220y of the chain 214 comes into engagement with the jack 222 and urges the latter in counterclockwise direction about its pivot 224 against the action of the spring 234, the yoke 230 is swung about its pivot 232 into such a position that its lower end 240 reaches the position 240' shown in dash and dot lines in Fig. 9. This, in turn, permits engagement of the spring loaded actuating pawl 242 with teeth of the ratchet wheel 250, so that the latter and the selector drum 252 connected therewith are advanced a step when the actuating pawl 242 is moved by the double-armed lever 248. The ratchet wheel 250 is held in the advanced position by a spring loaded locking pawl 254 rockably mounted on the shaft 212. The stepwise rotation of the selector drum 252 takes place in the direction of the arrow B, oppositely to the stepwise rotation of the controlling drum 208 in the direction of the arrow A.

25 55 60 65 60 As soon as the button 220y of the chain 214 is past the spring loaded jack 222 and there is no new button on the chain 214 opposite said jack 222, the latter is returned by its spring 234 into the position shown in Fig. 9, whereby the actuating pawl 242 is brought out of engagement with teeth of the ratchet wheel 250 and, thus, the actuating pawl 242 is again rendered ineffective.

65 Above mentioned movement of the actuating pawl 242 is obtained by the following mechanism:

65 As best shown in Figs. 4, 7 and 13 a cam 256 keyed to the cam shaft 44 rotated by the power driven main cam shaft 28 through the train of gears 28-42 is arranged for cooperation with a

roller 258 carried by the arm 260 of a double-armed follower 262 freely rotatably mounted on a shaft 264 carried by the bracket 87. The other arm 266 of said follower 262 is pivotally connected at 268 with the upper end of an adjustable rod 270, the lower end of which is pivoted at 272 with an arm 274 of the double-armed lever 248, which carries at its other arm 246 the spring-loaded actuating pawl 242 in the manner described above (see Figs. 9-11 and 13). Thus, during the operation of the machine the actuating pawl 242 is continuously moved back and forth by the cam 256 through the linkage 262, 270 and 248. However, as explained above, this movement of the actuating pawl 242 forming a coupling means of a coupling mechanism has no influence on the ratchet wheel 250—forming the other coupling means of a coupling mechanism—and the selector drum 252 connected therewith as long as the yoke 230 conditioning the position of the actuating pawl 242 is held in the position shown in full lines in Fig. 9. When, however, upon a stepwise rotation of the controlling drum 208, a button 220y of the chain 214 swings the jack 222 into such a position that the lower end 240 of the yoke 230 reaches the position 240', each advance movement of the actuating pawl 242 causes a stepwise rotation of the ratchet wheel 250 and the selector drum 252, as long as such a button 220y holds the jack 222 and the yoke 230 in the position permitting engagement between the actuating pawl 242 and teeth of the ratchet wheel 250.

According to Fig. 4, there are four pattern arms 78-3, 78-4, 78-5 and 78-6, each of which having an upper end 76-3, 76-4, 76-5 and 76-6 detachably mounted thereon by means of screws. For example, as shown in Fig. 8, the end 76-5 is attached to the pattern arm 78-5 by means of screws 276. Each of the ends 76-3, 76-4, 76-5 and 76-6 is arranged for engagement with a slider 66-3, 66-4, 66-5 and 66-6 respectively, associated with a guide bar 50-3, 50-4, 50-5 and 50-6 respectively.

All of these pattern arms 78-3, 78-4, 78-5 and 78-6 are rockably mounted on the shaft 80. As best shown in Fig. 4, the pattern arms 78-3, 78-4, 78-5 and 78-6 are held in proper position by means of spacers 278 secured to and projecting from the bracket 87.

On each of the pattern arms 78-3, 78-4, 78-5 and 78-6 a selector latch is swingably mounted. For the sake of better illustration, Fig. 4 illustrates only the selector latch 280-5 arranged on the pattern arm 78-5, but it is understood that the same type of selector latch is swingably mounted on each of the pattern arms 78-3, 78-4, 78-5 and 78-6, and that each selector latch of each pattern arm cooperates with three spring-loaded controlling arms, each of which in turn cooperates with a pattern chain on the lower pattern chain drum 156, in the same manner, as will be described herein-after in connection with the selector latch 280-5 of the pattern arm 78-5. As best shown in Fig. 8, the selector latch 280-5 is swingably mounted on a pin 282-5 projecting downwardly from the pattern arm 78-5. As best shown in Figs. 14-16, the selector latch 280-5 may be set into three different positions, so that its free end is either above a controlling arm 284-5-a (Fig. 14) or above a controlling arm 284-5-b (Figs. 4, 8 and 15) or above a controlling arm 284-5-c (Fig. 16). Each of said controlling arms 284-5-a, 284-5-b, and 284-5-c is swing-

ably mounted on the shaft 174 and carries a roller 286-5-a, 286-5-b, and 286-5-c respectively (see Fig. 4). Each controlling arm is subject to the action of a spring 288 stretched between the arm and a stationary element (shaft 171 (Figs. 4 and 7) of the machine) for urging the roller 286-5-a, 286-5-b, 286-5-c into engagement with the associated pattern chain 166-5-a, 166-5-b, 166-5-c respectively, trained around the lower pattern chain drum 156. As will be readily understood, the movements of the pattern arm 78-5 and the associated guide bar 50-5 are controlled by the pattern chain 166-5-a or 166-5-b or 166-5-c in dependence on the position of the selector latch 280-5, i. e. if the free end of the selector latch 280-5 is above the controlling arm 284-5-a, (Fig. 14) the movements of the pattern arm 78-5 and guide bar 50-5 are controlled by the pattern chain 166-5-a, if the free end of the selector latch 280-5 is above the controlling arm 284-5-b (Figs. 4, 8 and 15), the movements are controlled by the pattern chain 166-5-b, and if the free end of the selector latch 280-5 is above the controlling arm 284-5-c (Fig. 16), the movements are controlled by the pattern chain 166-5-c.

In order to obtain an automatic adjustment of the portion of the selector latches swingably arranged on the pattern arms 78-3, 78-4, 78-5 and 78-6, the machine is provided with the following mechanism:

It is sufficient to describe hereinafter the control of the selector latch 280-5, as the other selector latches are controlled in the same manner.

As best shown in Figs. 4, 8 and 14-16, one end of a wire 290-5 is pivotally engaged with an arm of the selector latch 280-5, as shown in Figs. 4, 9-11 and 14-16, the other end of the said wire 290-5 is engaged with a bore of a jack 292-5 swingably mounted on a shaft 294 carried by the bracket 87. In a manner known per se, the wire 290-5 is yieldably connected with the jack 292-5 by means of collars 293, 295, 297 secured to the wire and a spring 299 arranged between the collars 295 and 297. A spring 296 stretched between a stationary point 298 and an extension 300 of the jack, tends to urge the latter against a stop rod 302.

Each of the latches (not shown) associated with the pattern arms 78-3, 78-4 and 78-6 is connected by a wire 290-3, 290-4 and 290-6 (see Figs. 4, 10 and 11) with a spring-loaded jack 292-3, 292-4 and 292-6 respectively, each of which is also swingably mounted on the shaft 294.

The series of jacks 292-3, 292-4, 292-5 and 292-6 cooperates with a pattern chain 304 (see Figs. 4 and 9-11) trained around the selector drum 252 and an idling roller 306 carried by the rod 218.

The ladder chain 304 is provided with four rows of buttons 308-3, 308-4, 308-5 and 308-6, the first row cooperating with the jack 292-3, the second row cooperating with the jack 292-4, the third row cooperating with the jack 292-5 and the fourth row cooperating with the jack 292-6. As best shown in Fig. 9, the buttons are of different heights. For example, the button 308-5-b is comparatively low, while the button 308-5-c is high.

As long as there is no button opposite the projection 310-5 of the jack 292-5 (see Fig. 9) the spring associated with said jack 292-5 urges

same into the position shown in Fig. 9, whereby the selector latch 280-5 is held in the position shown in Fig. 14 with its free end above the controlling arm 284-5-a.

When, during above described stepwise rotation of the selector drum 252 a low button 308-5-b comes into engagement with the projection 310-5 of the jack 292-5, the selector latch 280-5 is swung into the position shown in Fig. 15, wherein its free end is above the controlling arm 284-5-b.

When, during the intermittent rotation of the selector drum 252 a high button 308-5-c comes into engagement with the projection 310-5 of the jack 292-5, the selector latch 280-5 is swung into the position shown in Fig. 16, wherein its free end is above the controlling arm 284-5-c.

Thus, the selector drum 252 controls the positions of the selector latches relative to the controlling arms associated therewith for causing an actuation of the pattern arms and the guide bars associated with the latter by one of three pattern chains trained around the lower pattern chain drum 156 and associated with the respective pattern arm.

As can be readily gathered from Fig. 8, the weight of the swingable pattern arms 78 rests on the selector latches 280 associated therewith. In order to render possible a smooth setting of the selector latches 280 from one position into another one, it is desirable to relieve the selector latches from the pressure acting thereon before a setting operation takes place. This feature may be obtained by the following relieving mechanism:

As may be gathered from Figs. 4, 8 and 12, each of the pattern arms 78-3, 78-4, 78-5, 78-6 is associated with an arm 312-3, 312-4, 312-5 and 312-6 keyed to the shaft 264, each of the setting arms being arranged for abutment against an adjustable threaded bolt projecting from the associated pattern arm. At the end of the shaft 264 an arm 314 is rigidly connected with said shaft by a screw 316. A spring 318 stretched between the end of the arm 314 and a stationary point of the machine tends to urge an adjustable bolt 320 projecting from the arm 314 against a stop 322 arranged on the machine.

Furthermore, the arm 314 carries a latch 324 swingably mounted on a pin 326 projecting from the arm 314. This latch normally is in the position shown in full lines in Fig. 12, so that an oscillating movement of a spring-loaded follower 328 carried by a shaft 330 and actuated by a cam 332 keyed to the cam shaft 44, has no influence on the arm 314.

One end of a wire 334 is pivotally engaged with an arm 336 of the latch 324. The other end of said wire 334 passing through a bore of a jack 338 (see Figs. 9-12) swingably mounted on the shaft 224 is yieldably connected with said jack by collars 339, 341, 343 secured to said wire and a spring 345 arranged between the collars 341 and 343. The jack 338 is normally held by a spring 340 (see Fig. 11) stretched between its extension 342 and the shaft 236 in engagement with the stopping rod 232, so that in turn the latch 324 is in the position shown in Fig. 12.

The jack 338 cooperates with buttons 220s (see Fig. 11) of the chain 214 trained around the controlling drum 208. If, upon an intermittent rotation of the controlling drum 208 a button 220s comes into engagement with the jack 338, the latter is swung against the action of its spring in counterclockwise direction, as viewed in Fig.

9, whereby the wire 334 is shifted in the direction of the arrow C (see Fig. 12), so that the latch 324 is brought into the position 324' shown in dash and dot lines in Fig. 12. Now the latch 5 is below the adjustable screw 344 carried by the follower 328, so that upon a depression of the follower 328 by the cam 332 cooperating with a roller 346 mounted on the follower 328, the arm 314 is rocked in the direction of the arrow D causing a lifting of all of the pattern arms 78-3, 78-4, 78-5 and 78-6 by the arms 312-3, 312-4, 312-5, 312-6 in the direction of the arrow E shown in Fig. 12. This lifting, in turn, results in a disengagement of the lower surface 15 of the selector latches 280 from the adjustable screws carried by the associated controlling arms 284, so that now one or more of the selector latches 280 may be readily displaced from one position into another one by an action of the selector drum 252 through one or more of the jacks 292 and wire 290 in the manner described above, when the selector drum 252 is advanced for this purpose.

Summarizing:

25 The upper pattern chain drum 74 is continuously rotated, at constant speed or at variable speed (depending on the setting of the pins 132 and 140 cooperating with the cam portion 120) by the main drive. The endless pattern chains 30 72-1, 72-2, 72-7, 72-8 trained around the upper pattern chain drum 74 cause a longitudinal shifting of the guide bars 50-1, 50-2, 50-7 and 50-8 at predetermined intervals.

35 The lower pattern chain drum 156 is permanently rotated by the upper pattern chain drum 74 at the same speed, constant or varying.

30 The lower pattern chain drum 156 causes a longitudinal shifting of the guide bars 50-3, 50-4, 50-5 and 50-6 at predetermined intervals through the pattern arms 78-3, 78-4, 78-5 and 78-6 in dependence on the position of the latch selectors 280-3, 280-4, 280-5 and 280-6, which select the pattern controlled by one of three chains trained around the lower pattern chain drum 156 and associated with one of the four pattern arms 78-3, 78-4, 78-5 and 78-6.

40 The continuously rotating lower pattern chain drum 156 also controls stepwise rotations of the controlling drum 208.

45 The intermittently rotated controlling drum 208 determines the time interval when a stepwise rotation of the selector drum 252 may take place and controls the time interval when the selector latches are relieved from pressure acting thereon, so that an automatic setting of one or more selector latches may take place.

50 The intermittently rotated selector drum 252 controls the positioning of the selector latches, whereby, in turn, as described above, the pattern chain on the lower pattern chain drum is selected for the control of the associated pattern arm for controlling movements of the guide bar associated with the latter.

55 The contour of the track 128 (Figs. 5 and 6) of the drum cam is designed in such a way, that the speed of the worm gear 146 operatively connected with the upper pattern chain drum 74 and through the latter and the chain 150 (see Figs. 4 and 7) with the lower pattern chain drum is accelerated during the so-called lapping around operation of the guides in front of the needles for the formation of stitches and that the speed 70 of said worm gear 146 is retarded during the so-

called long-shifting operation of the guides behind the needles.

As will be readily understood from above, the machine according to the invention has only one pattern arm or controlling element (78-5) and only one selector (280-5) for each of the inner guide bars (50-5), so that only three link-pattern-chains (166-5-a, 166-5-b, 166-5-c) on the lower pattern chain drum (156) and only one row of buttons (308-5) on a ladder-selecting-chain (304) on a selector drum (252) are required for each inner guide bar, in contrast to six link-chains in hitherto customary machines wherein three controlling elements and three selectors (one for each controlling element) are associated with each inner guide bar. This feature of a machine according to the invention renders same less expensive in the manufacture and use; also the entire automatic pattern controlling device becomes less bulky.

Furthermore, the selection of the patterns by the selector latches 280 renders possible smooth and practically noiseless operation; moreover, the selection of the patterns by selector latches, which may be readily set into various positions, permits the operation of the machine at a comparatively high speed.

Furthermore, in accordance with the construction of the automatic controlling device according to the invention, ladder chains 214 and 304 may be used on the controlling drum 208 and the selector drum 252, which ladder chains are less expensive than link chains used in hitherto known devices for the automatic control of the pattern. Furthermore, the use of the comparatively cheap ladder chains renders it feasible, from an economical point of view, to maintain a supply thereof, so that if, after the operation of the machine for a period of time, it is desired to change the pattern of the fabric to be knitted, the operator may remove from the machine the ladder chains with the buttons arranged thereon for a certain pattern, store the chains away for future use and replace same by other ladder chains with buttons arranged thereon for the new pattern.

The direct connection between the upper pattern chain drum 74 and the lower pattern chain drum 156 by the chain 150 assures a constant relationship between the pattern chains, which is especially of advantage when, occasionally, the machine is turned by hand.

Moreover, the warp knitting machine may be operated with standard pattern mechanism, if so desired. For this purpose it is merely necessary to remove the chain 150 between the upper and lower pattern chain drums 74 and 156, to detach the upper ends 76 from the pattern arms 78, to attach rollers to the sliders 66-3, 66-4, 66-5 and 66-6 and to apply link pattern chains to the grooves 96-3, 96-4, 96-5, 96-6 of the upper pattern chain drum 74.

I have described a preferred embodiment of my invention, but it is understood that this disclosure is for the purpose of illustration, and that various omissions or changes in shape, proportion and arrangement of parts, as well as the substitution of equivalent elements for those herein shown and described may be made without departing in any way from the spirit and scope of this invention as set forth in the appended claims.

What I claim is:

1. In a warp knitting machine, the combination of: a main drive, a plurality of movable

guide bars capable of performing reciprocating movements in the direction of the longitudinal axis of the machine, a series of controlling elements movably mounted in the machine, each of said controlling elements being arranged for operative connection with another one of said guide bars for the control of reciprocating movements of the latter, a pattern chain drum rotatably mounted on said machine and driven by said main drive, a plurality of pattern chains trained around said pattern chain drum, a predetermined number of said pattern chains, at least two thereof, being associated with each of said controlling elements for the control of movements of the latter, a series of movable selectors equal in number to the number of controlling elements, each of said selectors being associated with one of said controlling elements and being settable in various positions for selecting one of the pattern chains associated with the respective controlling element for controlling the movements of the latter, and a pattern mechanism actuated by said main drive, said pattern mechanism being associated with said selectors for setting same in predetermined positions at predetermined intervals during the operation of the machine.

2. In a warp knitting machine as claimed in claim 1, said pattern mechanism including movable selecting means, arranged for actuation by the main drive and for controlling said selectors, and movable controlling means arranged for controlling the movements of said selecting means by said main drive, additional pattern chain means driven by said main drive, and an actuating mechanism controlled by said additional pattern chain means and associated with said controlling means for actuating the latter at predetermined intervals during the operation of the machine.

3. In a warp knitting machine, the combination of: a main drive, a plurality of movable guide bars capable of performing reciprocating movements in the direction of the longitudinal axis of the machine, a series of controlling elements movably mounted in the machine, each of said controlling elements being arranged for operative connection with another one of said guide bars for the control of reciprocating movements of the latter, a pattern chain drum rotatably mounted in said machine and driven by said main drive, a plurality of pattern chains trained around said pattern chain drum, a predetermined number of said pattern chains, at least two thereof, being associated with each of said controlling elements for the control of movements of the latter, a series of latch selectors equal in number to the number of controlling elements, each of said latch selectors being rockably mounted on one of said controlling elements and being settable in various positions in register with one of the pattern chains associated with the controlling element carrying the latch selector whereby the pattern chain for controlling the movements of the respective controlling element may be selected, and a pattern mechanism actuated by said main drive, said pattern mechanism being associated with said latch selectors for setting same in predetermined positions at predetermined intervals during the operation of the machine.

4. In a warp knitting machine as claimed in claim 3, a plurality of arms movably mounted in the machine, each arm being associated with one of said pattern chains and being arranged

13

between the latter and the latch selector carried by the associated controlling element.

5. In a warp knitting machine as claimed in claim 3, relieving means associated with said controlling elements for withdrawing same and the latch selectors somewhat from said pattern chains, and said pattern mechanism being associated with said relieving means for rendering same active prior to a setting of said latch selectors by said pattern mechanism.

6. In a warp knitting machine as claimed in claim 3, relieving means arranged for actuation by the main drive and associated with said controlling elements for withdrawing same and the latch selectors somewhat from said pattern chains, said pattern mechanism including movable selecting means, arranged for actuation by the main drive and for controlling setting movements of said latch selectors, and movable controlling means arranged for controlling the movements of said selecting means by said main drive and for controlling the movements of said relieving means by said main drive so as to cause a withdrawal of said controlling elements prior to setting movements of said latch selectors, additional pattern chain means driven by said main drive, and an actuating mechanism controlled by said additional pattern chain means and associated with said controlling means for actuating the latter at predetermined intervals during the operation of the machine.

7. In a warp knitting machine, the combination of: a main drive, a plurality of movable guide bars capable of performing reciprocating movements in the direction of the longitudinal axis of the machine, a series of double-armed controlling elements swingably mounted on the machine, each of said controlling elements being arranged for operative engagement of one of its arms with another one of said guide bars for the control of reciprocating movements of the latter, a series of latch selectors equal in number to the number of controlling elements, each of said latch selectors being rockably mounted on the other arm of one of said controlling elements and being settable in various positions in register with one of the pattern chains associated with the controlling element carrying the latch selector whereby the pattern chain for controlling the movements of the respective controlling element may be selected, and a pattern mechanism actuated by said main drive, said pattern mechanism being associated with said latch selectors for setting same in predetermined positions at predetermined intervals during the operation of the machine.

8. In a warp knitting machine as claimed in claim 7, a plurality of arms swingably mounted in the machine, each arm being associated with one of said pattern chains and being arranged between the latter and the latch selector carried by the associated controlling element.

9. In a warp knitting machine as claimed in claim 1, said pattern mechanism including a rotatable controlling chain drum and a rotatable selector chain drum, controlling chain means trained around said controlling chain drum, selecting chain means trained around said selector chain drum, additional pattern chain means driven by said main drive, a first actuating mechanism controlled by said additional pattern chain means and associated with said controlling chain drum for intermittently advancing the latter at predetermined intervals, and a second actuating mechanism driven by said main

14

drive and associated with said selector chain drum, said second actuating means including coupling means capable of operative engagement with and disengagement from said selector chain drum, said controlling chain means being associated with said coupling means for conditioning its engaging and disengaging positions whereby, upon conditioning of the engaging position, said selector chain drum is intermittently advanced by said second actuating means at predetermined intervals, and said selecting chain means being associated with said selectors for controlling the setting movements of the latter.

10. In a warp knitting machine as claimed in claim 1, said pattern mechanism including a rotatable controlling chain drum and a rotatable selector chain drum, controlling chain means trained around said controlling chain drum, selecting chain means trained around said selector chain drum, an additional pattern chain trained around said pattern chain drum, a first actuating mechanism controlled by said additional pattern chain and associated with said controlling chain drum for intermittently advancing the latter at predetermined intervals, and a second actuating mechanism driven by said main drive and associated with said selector chain drum, said second actuating means including coupling means capable of operative engagement with and disengagement from said selector chain drum, said controlling chain means being associated with said coupling means for conditioning its engaging and disengaging positions whereby, upon conditioning of the engaging position, said selector chain drum is intermittently advanced by said second actuating means at predetermined intervals, and said selecting chain means being associated with said selectors for controlling the setting movements of the latter.

11. In a warp knitting machine as claimed in 1, said selectors being movably mounted on said controlling elements and being arranged between said controlling elements and the associated pattern chains, movable relieving means associated with said controlling elements for withdrawing same and said selectors somewhat from said pattern chains, said pattern mechanism including a rotatable controlling chain drum and a rotatable selector chain drum, controlling chain means trained around said controlling chain drum, selecting chain means trained around said selector chain drum, additional pattern chain means driven by said main drive, a first actuating mechanism controlled by said additional pattern chain means and associated with said controlling chain drum for intermittently advancing the latter at predetermined intervals, and a second actuating mechanism driven by said main drive and associated with said selector chain drum, said second actuating means including coupling means capable of operative engagement with and disengagement from said selector chain drum, said controlling chain means being associated with said coupling means for conditioning its engaging and disengaging positions whereby, upon conditioning of the engaging position, said selector chain drum is intermittently advanced by said second actuating means at predetermined intervals, and said selecting chain means being associated with said selectors for controlling the setting movements of the latter, and said controlling chain means being also associated with said relieving means for rendering same active prior to a setting of said selectors.

12. In a warp knitting machine as claimed in

15

claim 11, a third actuating mechanism driven by said main drive, said third actuating mechanism including a movable coupling element capable of operative engagement with and disengagement from said relieving means, and said controlling chain means being associated with said coupling element for conditioning its engaging and disengaging positions whereby, upon conditioning of the engaging position, said relieving means are rendered active by said third actuating mechanism prior to a setting of said selectors.

13. In a warp knitting machine, the combination of: a main drive, a first series and a second series of movable guide bars capable of performing reciprocating movements in the direction of the longitudinal axis of the machine, a first pattern chain drum rotatably mounted in the machine and driven by said main drive, a series of upper pattern chains trained around said first pattern chain drum and associated with the first series of movable guide bars for the control of reciprocating movements thereof, a series of controlling elements, equal in number to the number of the second series of movable guide bars, movably mounted in the machine, each of said controlling elements being arranged for operative connection with another one of the guide bars of the second series of guide bars for the control of reciprocating movements thereof, a second pattern chain drum rotatably mounted in said machine and driven by said main drive, a plurality of second pattern chains trained around said second pattern chain drum, a predetermined number of said second pattern chains, at least two thereof, being associated with each of said controlling elements for the control of movements of the latter, a series of movable selectors equal in number to the number of controlling elements, each of said selectors being associated with one of said controlling elements and being settable in various positions for selecting one of the second pattern chains associated with the respective controlling element for controlling the movements of the latter, and a pattern mechanism actuated by said main drive, said pattern mechanism being associated with said selectors for setting same in predetermined positions at predetermined intervals during the operation of the machine.

14. In a warp knitting machine as claimed in claim 13, said first pattern chain drum being operatively connected with said second pattern chain drum for driving the latter.

15. In a warp knitting machine as claimed in claim 13, said first pattern chain drum being operatively connected with said second pattern chain drum for driving the latter, and means for varying the speed of the first pattern chain drum during a revolution of the latter being arranged between said main drive and said first pattern chain drum.

16. In a warp knitting machine, the combination of: a main drive, a first series and a second series of movable guide bars capable of performing reciprocating movements in the direction of the longitudinal axis of the machine, a first pattern chain drum rotatably mounted in the machine and driven by said main drive, a series of upper pattern chains trained around said first pattern chain drum and associated with the first series of movable guide bars for the control of reciprocating movements thereof, a series of double-armed controlling elements equal in number to the number of the second series of movable guide bars, swingably mounted

16

in the machine, the first arm of each of said double-armed controlling elements being arranged for operative connection with another one of the guide bars of the second series of guide bars for the control of reciprocating movements thereof, a second pattern chain drum rotatably mounted in said machine and driven by said main drive, a plurality of second pattern chains trained around said second pattern chain drum, a predetermined number of said second pattern chains, at least two thereof, being associated with each of said controlling elements for the control of movements of the latter, a series of movable selectors equal in number to the number of controlling elements, each of said selectors being associated with the other arm of one of said double-armed controlling elements and being settable in various positions for selecting one of the second pattern chains associated with the respective controlling element for controlling the movement of the latter, and a pattern mechanism actuated by said main drive, said pattern mechanism being associated with said selectors for setting same in predetermined positions at predetermined intervals during the operation of the machine.

17. In a warp knitting machine as claimed in claim 16, the arms of said double-armed controlling elements associated with the guide bars being detachable from the main body of each controlling element, and said first pattern chain drum being capable of receiving a second series of first pattern chains for cooperation with said second series of guide bars.

18. In a warp knitting machine as claimed in claim 16, said selectors being in the shape of latch selectors, each of said latch selectors being rockably mounted on the other arm of the associated double-armed controlling element and being settable in various positions in register with one of the second pattern chains associated with the controlling element carrying the selector.

19. In a warp knitting machine as claimed in claim 16, a series of arms equal in number to the number of second pattern chains, swingably mounted in the machine, each arm being arranged for cooperation with one of said second pattern chains, said selectors being in the shape of latch selectors, each of said latch selectors being rockably mounted on the other arm of the associated double-armed controlling element and being settable in various positions for engagement with one of the second pattern chains associated with the controlling element carrying the selector.

20. In a warp knitting machine as claimed in claim 13, said pattern mechanism including a rotatable controlling chain drum and a rotatable selector chain drum, controlling chain means trained around said controlling chain drum, selecting chain means trained around said selector chain drum, additional pattern chain means driven by said main drive, a first actuating mechanism controlled by said additional pattern chain means and associated with said controlling chain drum for intermittently advancing the latter at predetermined intervals, and a second actuating mechanism driven by said main drive and associated with said selector chain drum, said actuating means including coupling means capable of operative engagement with and disengagement from said selector chain drum, said controlling chain means being associated with said coupling means for conditioning its engaging and disengaging positions whereby, upon conditioning

of the engaging position, said selector chain drum is intermittently advanced by said second actuating means at predetermined intervals, and said selecting chain means being associated with said selectors for controlling the setting movements of the latter.

21. In a warp knitting machine as claimed in claim 13, said selectors being movably mounted on said controlling elements and being arranged between said controlling elements and the associated second pattern chain, movable relieving means associated with said controlling elements for withdrawing same and said selectors somewhat from said second pattern chains, said pattern mechanism including a rotatable controlling chain drum and a rotatable selector chain drum, controlling chain means trained around said controlling chain drum, selecting chain means trained around said selector chain drum, additional pattern chain means driven by said main drive, a first actuating mechanism controlled by said additional pattern chain means and associated with said controlling chain drum for intermittently advancing the latter at predetermined intervals, and a second actuating mechanism driven by said main drive and associated with said selector chain drum, said second actuating means including coupling means capable of operative engagement with and disengagement from said selector chain drum, said controlling chain means being associated with said coupling means for conditioning its engaging and disengaging positions whereby, upon conditioning of the engaging position, said selector chain drum is intermittently advanced by said second actuating means at predetermined intervals, said selecting chain means being associated with said selectors for controlling the setting movements of the latter, and said controlling chain means being also associated with said relieving means for rendering same active prior to a setting of said selectors.

22. In a warp knitting machine as claimed in claim 16, said selectors being in the shape of latch selectors, each of said latch selectors being rockably mounted on the other arm of the associated double-armed controlling element and being settable in various position in register with one of the second pattern chains associated with the controlling element carrying the selector, movable relieving means associated with said controlling elements for withdrawing same and said selectors somewhat from said second pattern chains, said pattern mechanism including a rotatable controlling chain drum and a rotatable selector chain drum, controlling chain means trained around said controlling chain drum, selecting chain means trained around said selector chain drum, additional pattern chain means driven by said main drive, a first actuating mechanism controlled by said additional pattern chain means and associated with said controlling chain drum for intermittently advancing the latter at predetermined intervals, and a second actuating mechanism driven by said main drive and associated with said selector chain drum, said second actuating means including coupling means capable of operative engagement with and disengagement from said selector chain drum, said controlling chain means being associated with said coupling means for conditioning its engaging and disengaging positions whereby, upon conditioning of the engaging position, said selector chain drum is intermittently advanced by said second actuating means at predetermined inter-

vals, said selecting chain means being associated with said selectors for controlling the setting movements of the latter, and said controlling chain means being also associated with said relieving means for rendering same active prior to a setting of said selectors.

23. In a warp knitting machine as claimed in claim 16, a series of arms equal in number to the number of second pattern chains, swingably mounted in the machine, each arm being arranged for cooperation with one of said second pattern chains, said selectors being in the shape of latch selectors, each of said latch selectors being rockably mounted on the other arm of the associated double-armed controlling element and being settable in various positions for engagement with one of the second pattern chains associated with the controlling element carrying the selector, movable relieving means associated with said controlling elements for withdrawing same and said selectors somewhat from said second pattern chains, said pattern mechanism including a rotatable controlling chain drum and a rotatable selector chain drum, controlling chain means trained around said controlling chain drum, selecting chain means trained around said selector chain drum, additional pattern chain means driven by said main drive, a first actuating mechanism controlled by said additional pattern chain means and associated with said controlling chain drum for intermittently advancing the latter at predetermined intervals, and a second actuating mechanism driven by said main drive and associated with said selector chain drum, said second actuating means including coupling means capable of operative engagement with and disengagement from said selector chain drum, said controlling chain means being associated with said coupling means for conditioning its engaging and disengaging positions, whereby, upon conditioning of the engaging position, said selector chain drum is intermittently advanced by said second actuating means at predetermined intervals, said selecting chain means being associated with said selectors for controlling the setting movements of the latter, and said controlling chain means being also associated with said relieving means for rendering same active prior to a setting of said selectors.

24. In a warp knitting machine as claimed in claim 16, a series of arms, equal in number to the number of second pattern chains, swingably mounted in the machine, each arm being arranged for cooperation with one of said second pattern chains, said selectors being in the shape of latch selectors, each of said latch selectors being rockably mounted on the other arm of the associated double-armed controlling element and being settable in various positions for engagement with one of the second pattern chains associated with the controlling element carrying the selector, movable relieving means associated with said controlling elements for withdrawing same and said selectors somewhat from said second pattern chains, said pattern mechanism including a rotatable controlling chain drum and a rotatable selector chain drum, controlling chain means trained around said controlling chain drum, selecting chain means trained around said selector chain drum, an additional pattern chain trained around said second pattern chain drum, a first actuating mechanism controlled by said additional pattern chain and associated with said controlling chain drum for intermittently advancing the latter at predetermined intervals,

19

and a second actuating mechanism driven by said main drive and associated with said selector chain drum, said second actuating means including coupling means capable of operative engagement with and disengagement from said selector chain drum, said controlling chain means being associated with said coupling means for conditioning its engaging and disengaging positions whereby, upon conditioning of the engaging position, said selector chain drum is intermittently advanced by said second actuating means at predetermined intervals, said selecting chain means being associated with said selectors for controlling the setting movements of the latter, and said controlling chain means being also associated with said relieving means for rendering same active prior to a setting of said selectors.

15 25. In a warp knitting machine as claimed in

20

claim 24, a third actuating mechanism driven by said main drive, said third actuating mechanism including a movable coupling element capable of operative engagement with and disengagement from said relieving means, and said controlling chain means being associated with said coupling element for conditioning its engaging and disengaging positions whereby, upon conditioning of the engaging position, said relieving means are rendered active by said third actuating mechanism prior to a setting of said selectors.
